[57] CLAIM

The ornamental design for a spool for a fishing reel, as shown and described.

DESCRIPTION

FIG. 1 is a plan view of a spool for a fishing reel showing my new design, it being understood that the spool is symmetrical about its axis;

FIG. 2 is an end view thereof taken from the left in FIG. 1; and

FIG. 3 is an end view from the opposite end to that shown in FIG. 2.
